UNITED STATES PATENT OFFICE.

PETER T. KAVANAGH, OF CHICAGO, ASSIGNOR TO HYPPOLITE BOUSSE-MAERE, OF LAKE VIEW, ILLINOIS.

PHOTOGRAPH-CASE.

SPECIFICATION forming part of Letters Patent No. 392,563, dated November 6, 1888.

Application filed October 22, 1887. Serial No. 253,135. (No model.)

To all whom it may concern:

Be it known that I, PETER T. KAVANAGH, a subject of the Queen of Great Britain, residing at Chicago, in the county of Cook and State 5 of Illinois, have invented certain new and useful Improvements in Photograph-Cases, of which the following is a specification.

My invention relates to the class of photograph-cases for containing photographs in endless series and provided with means for turning the photographs to bring them readily and successively to a plane convenient for inspection.

The object of my improvement is to provide 15 a construction of case which shall, better than cases for the purpose as hitherto constructed, adapt it to permit convenient and advantageous display of the photographs by rendering it capable of being swung about a horizontal 20 axis to any desired angle in the vertical plane of its movement, and which shall render it light and small compared with the weightiness and bulk heretofore incident to the cases of photograph-exhibitors.

To the attainment of the foregoing ends my 25 invention consists in the general construction of the case; and it also consists in details of construction and combinations of parts.

In the drawings, Figure 1 represents in elevation my improved photograph-case supported to swing about a horizontal axis, a portion of the case being broken away. Fig. 2 is a detail representing in section one of the pivotal supports for the case. Fig. 3 represents 35 in perspective one of the series of photograph holders or frames to contain which the case is provided. Fig. 4 represents one of the square rotary shafts for supporting the frame or holders. Fig. 5 is an edge view of the frame represented in Fig. 3, and shows the same applied to the endless band, of which latter only a small portion is represented. Fig. 6 is a face view of the spring bearing-plate that is shown 40 in section in Fig. 2.

A is the case for containing a collection of photographs supported therein in endless series and for permitting them to be brought successively to convenient and advantageous view. The case A comprises the body portion a', preferably of opaque material, which

may be and preferably is rounded toward its base from its lateral sides and flat, or substantially so, on its front and rear sides.

G is a base or stand carrying a yoke-shaped supporting-frame, F, which should be swiveled 55 upon the base and may be ornamented at its extremities, as shown, and the case A is supported on horizontal journals E, extending from its opposite sides and mounted in the upper ends of the yoke F. 6c

By the foregoing construction the case may be readily turned both in a horizontal plane on the vertical axis afforded by the swivel and in a vertical plane on its horizontal pivotal supports to bring it into the most desirable 65 position for inspection of the photographs within it, and which may be arranged in frames, as follows:

B B are the photograph holders or frames, forming skeleton leaves, each adapted to hold 70 one or more photographic cards, two of which may be arranged back to back in each frame, so that they may respectively be viewed from opposite sides of the frame. The frames B are flexibly connected in endless series along 75 what may be termed their "inner edges," whereby their opposite edges may be swung successively apart when the connected edges pass around a bend or corner, such as a roller.

The connecting medium herein shown for 8c the leaves B is an endless flexible belt, C, which is arranged to pass over rollers D and D' in the case and mounted horizontally one above the other. Each leaf B is secured along one of its edges to the belt C, as shown in Figs. 1 and 85 5, and the leaves or frames attached are so close together that if the belt were severed at any line and drawn out straight the frames would all abut and be flat against one another in regular series, as illustrated by the several 90 horizontally-extending frames shown in Fig. 1. By turning one of the rollers the endless belt is caused to travel over both, and thereby bring the frames successively to a position at the opening in the top of the case at which the 95 photographs are to be viewed.

To protect the photographs contained within the case, I provide means for closing the latter in the form of a suitable hinged cover, a, which may be of glass and rounded, as shown, 100

like the base of the case, when the photographs may be manipulated to bring them successively to view (by turning the roller D at the knob on its extremity, which projects beyond the case) without requiring the cover to be removed.

As shown in Fig. 1, the rollers D and D' are formed with four sides, each side being equal in width to the thickness of the edge portion 10 of each card-holding frame, whereby when the roller D is turned one of the series of frames B may be brought to a vertical position extending upward, while the frames at opposite sides of the temporarily upright frame will extend horizontally from the belt and the lowest frame of the series will hang. A quarter-turn of the roller D, say, toward the right from the position in which it is shown in Fig. 1 will, by causing the belt to travel, swing the 15 upright frame to a horizontal position, while the next following frame will be raised from its horizontal to an upright position. Each quarter of a turn of the roller D produces repetition of the operation thus described.

25 In Figs. 3 and 5 are illustrated a construction of the leaves B which is desirable for its lightness and durability, and comprising thin or sheet metal having a polygonal strip, B', preferably of wood, secured along one edge 30 and glued or cemented to the endless band C. When this form of frame is provided, it should have near its corners lugs or lips b, to be attached to the ends of the wooden strip, while other suitable fastenings may be employed between such points, if necessary. While it is 35 preferred that the upper roller, D, shall be provided with a suitable knob or handle at which to turn it, a knob may also, or instead, be on the lower roller.

40 The concavo-convex plate H herein shown is simply a spring-washer or bearing-plate arranged between the casing and a bearing for the journal E in the yoke F, to serve in preventing undue swinging of the case. Any other 45 suitable friction device may, however, be applied for the purpose; or the same may, if desired, be omitted.

The foregoing description of the mechanism within the case is only intended to be sufficiently explicit, as presenting one form of mechanism for its purpose, to convey a general idea of the manner of its operation, in order that the purpose and functions of the case, to which alone my invention relates, may 55 be rendered the more clear.

What I claim as new, and desire to secure by Letters Patent, is—

1. A tilting photograph-case comprising, in combination, a body portion, a', open at one end and provided with a cover, a, for closing 60 the open end, an endless series of frames flexibly connected together and supported within the case and provided with means for turning them, a suitable supporting-frame, and journals E, extending from opposite sides of the 65 body portion a' and supporting it pivotally on the frame, whereby the body portion is oscillatory on its support and adjustable thereon to bring the open end, through which the photograph-frames are projected, to a desired angle 70 for convenience of display, substantially as described.

2. A tilting photograph-case comprising, in combination, a body portion, a', rounded toward its base and open at its upper end and 75 provided with a cover, a, for closing the open end, an endless series of frames flexibly connected together and supported within the case and provided with means for turning them, a suitable supporting-frame, and journals E, ex- 80 tending from opposite sides of the body portion a' and supporting it pivotally on the frame, whereby the body portion is oscillatory on its support and adjustable thereon to bring the open end, through which the photograph-frames are projected, to a desired angle for 85 convenience of display, substantially as described.

3. A tilting photograph-case comprising, in combination, a body portion, a', open at its 90 upper end and provided with a hinged cover, a, an endless series of frames flexibly connected together and supported within the case and provided with means for turning them, a stand, G, a yoke, F, supported on the stand, 95 and journals E, extending from opposite sides of the body portion a' and supporting it pivotally on the yoke, whereby the body portion is oscillatory on its support and adjustable thereon to bring its open end, through which the photograph-frames are projected, to a desired angle for 100 convenience of display, substantially as described.

In witness whereof I have hereunto signed my name in the presence of two subscribing 105 witnesses.

PETER T. KAVANAGH.
